METHOD OF STRETCHING AND ASSEMBLING SHOE UPPERS ON LASTS

Euclid I. La Chapelle, Brockton, Mass.

Application September 1, 1942, Serial No. 456,954

14 Claims.

(Cl. 12—145)

My invention relates to a method of stretching and assembling uppers on lasts preparatory to the performance of the pulling over machine operation.

This application contains subject matter in common with application Serial No. 388,804, filed April 16, 1941, of which it is a continuation in part.

The first step in the lasting of a shoe is the assembling operation which generally is performed by hand with the aid of lasting pincers. Once a counter has been provided and a coating of cementitious material has been applied upon both the inside and the outside thereof, it is inserted between the upper proper and its lining and then the upper is next assembled on a last on which an insole has been previously assembled and then the shoe is set on a bench spindle and the upper and its lining located at the heel-end of the last are engaged and stretched heightwise of the last and over the insole by means of the hand lasting pincers and then, while the workman forces the upper, its lining and the counter against the heel-end of the last with his left hand, he drives a tack through the upper, its lining, the counterflange and the insole—the tack clinching against the heel-plate of the last.

Many difficulties are encountered at the pulling over machine operation, which is the second step in the lasting of the shoe, and with the aim in view of attaining better results and of facilitating the pulling over machine operation, it has been proposed to provide in an assembling machine stretching means, such as adapted to stretch the upper lengthwise from the heel-end to the toe-end of the last, but such shoe upper stretching means in an assembling machine never have been adopted in a commercial sense. It has been proposed also to perform a moulding operation upon a shoe upper to pre-form the upper to the approximate shape of a last prior to the assembling operation. But to thus prepare a shoe upper prior to the assembling operation prohibitively increases the cost of lasting shoes since an additional lasting operation then must be added to the usual lasting steps in the lasting of the shoe. In any event, so far as I am aware, such proposed shoe upper moulding operation never has been adopted in a commercial sense. Furthermore, it has been proposed to drive tacks at each side of the heel-seat of a shoe at the assembling operation, through the upper, the counterflange and the insole—the tacks clinching against the heel-plate of the last. This form of assembling aimed towards firmly setting the upper and

the counter in heel-seat formation, on the heel-end of the last, for making possible a better and easier heel-seat lasting machine operation and a better and easier pulling over machine operation, in that the toe-end pulling over machine movement upon the shoe upper then would be far less strenuous, so that the forepart of the upper located on top of the last, back of the toe, then would not be lifted and strained so forcibly, as heretofore had been the case, away from the last and so that this most difficult portion of the upper to last properly then would be more easily brought down to the last and with far less danger of damage to the lining located at the ball line of the last which oftentimes is torn under the strain of the grippers of a pulling over machine provided with grippers adapted to engage and stretch the upper at the ball line of the last. This proposed form of assembling, however, failed of success, as the lower marginal portion of the upper in binding even under the influence of the then less forcible toe-end pulling over movement of the pulling over machine would cause the upper to tear against the said tacks located at the sides of the heel-seat of the shoe and this form of assembling has been abandoned and only one tack is still being driven at the heel-end of the last at the assembling operation and a very strenuous pulling over movement by the toe-end grippers of the pulling over machine still has to be relied upon to firmly set the upper and the counter on the heel-end of the last.

From my long experience in the science of lasting and pulling over boots and shoes I have been led to reason and therefrom to conceive the herein disclosed method which has for objective the elimination of the defective conditions herein stated existing at the pulling over machine operation and, primarily, the elimination of the most serious defective condition existing at the pulling over machine operation and which is at the ball line of the last where excessive straining action by the grippers of the pulling over machine heretofore has been required.

As herein shown, described and recited in some of the claims, my method is intended for and does eliminate this serious condition at the ball line of the last at the pulling over machine operation in bringing about far less need of straining action by the grippers of the pulling over machine at or approximately at the ball line of the last in stretching the upper heightwise of the last and therefore far less liability of damage to the upper and/or its lining at that portion of the last in stretching and thereby in firmly setting the fore-

part of the upper on the last at the sides of or in close proximity to the ball line of the last and on top of the last in the hollow back of the toe, as good pulling over practice dictates.

At this point it may be stated that boots and shoes generally are pulled over by machine as a hand performed pulling over operation is the most laborious operation in shoemaking, but the desired results are difficult of attainment in pulling over shoes by machine and in many instances serious damage in the tearing of the upper and/or of its lining takes place. For instance, once the toe-end of the shoe upper has been pulled over by machine, while the upper is under sequential lengthwise strain and binds along its lower marginal portion from the heel-end to the toe-end of the last, the operator in then manipulating the grippers located at the sides of the toe to further stretch lengthwise of the last the binding lower marginal portion of the upper from the heel-end of the last to set the tip-seam straight on the last, oftentimes overstrains the upper and its lining and then either of which or both of which tear in the vicinity of the tip-seam.

The stretching lengthwise of the lower marginal portion of the upper at the assembling operation in accordance with the practice of my method also eliminates this serious defective condition at the pulling over machine operation.

In this connection it is important to explain that in view of overcoming the heretofore undue binding of the lower marginal portion of the upper lengthwise of the last at the pulling over machine operation, which precludes the working of the lower marginal portion of the upper to its proper extent of stretch in a direction towards the toe of the last without liability of damage to the upper and/or its lining in the setting of the tip-seam straight on the last, the practice of the herein disclosed method invariably dictates that the extent of the lengthwise stretch upon the lower marginal portion of the upper be in excess of the extent of the lengthwise stretch upon the top portion of the upper. This method of stretching the lower marginal portion of the upper at the assembling operation as above explained, eliminates undue binding of the lower marginal portion of the upper at the pulling over machine operation as the lengthwise stretched marginal portion of the upper then corresponds, as to the extent of lengthwise stretch, with or approximately with the extent of the lengthwise stretch upon the top portion of the upper taking place at the pulling over machine operation which, due to the then lengthwise stretch upon the top portion of the upper taking place from the toe-end portion of the upper, invariably is in excess of the lengthwise stretch upon the top portion of the upper that has already taken place, as herein proposed, at the assembling operation. Still further explained, such a greater extent of lengthwise stretch upon the top of the upper at the pulling over machine operation is due to the fact that the pulling over movement at the toe-end of the upper is the first performed pulling over movement and which serves to stretch and draft the top of the upper, and the lower marginal portion of the upper to a lesser extent of stretch, lengthwise of the last from the heel to the toe and therefore which must be most strenuous; but notably so due to the requirements of the subsequent final lasting step upon the toe-end of the upper which call for a most strenuous pulling over movement of the toe-end of the up-

per to fully stretch and thereby bring about proper mould of the toe-end of the upper (and of the toe-box when present) on the extreme toe-end of the last.

But, a still more serious defective condition exists at the pulling over machine operation whenever the pulling over machine is provided with grippers adapted to engage and stretch the upper heightwise of the last at the ball line of the last, in that the portion of the upper located over the top of the forepart of the last, back of the toe, is thereby forced down towards the last with great strain upon the upper and its lining which oftentimes causes tearing of the lining located at the center of the forepart of the upper. Such damage to the lining is so prevalent at the pulling over machine operation whenever the pulling over machine is provided with grippers adapted to engage and stretch the upper heightwise of the last at the ball line portion of the last, that in some shoe factories rubber cement is applied between the forepart of the upper proper and the lining, so that in the event of the lining being torn at the center of the forepart of the upper by the straining action of the aforesaid grippers located at the ball line of the last, the torn lining then may readily adhere to the upper proper and thus still offer a smooth inner shoe surface but as to the eventual reaction upon the wearer's foot of such a rubberized shoe forepart, one may easily surmise.

My herein disclosed method greatly helps towards eliminating the above noted defective condition at the pulling over machine operation by stretching lengthwise toward of the last the lower marginal portion of the shoe upper at the assembling operation so that far less strain then is required at the toe-end pulling over machine movement which causes the upper to lift and bind over the forepart of the last, as hereinbefore explained, and my method also helps in this direction by holding the back of toe portion of the upper in fastened curved condition preparatory to the performance of the pulling over machine operation. Moreover, my method also helps to a still greater extent in this direction by the application of fastenings at the ball line of the last to hold the upper in lengthwise stretched condition and in last shaped condition on the forepart of the last at the assembling operation preparatory to the pulling over machine operation.

A further defective condition, and which is a costly one to the shoe manufacturer, exists at the pulling over machine operation, in that under the effect of the strain incident to the toe-end pulling over movement upon the upper, the back-seam oftentimes is moved out of alignment relatively to the heel-end of the last so that a costly hand performed operation then is in order in the straightening out of the back-seam after the performance of the pulling over machine operation by means of the hand hammer and the hot iron and then the straightening out of the back-seam is only temporary as it again will assume its original crooked condition after a short time of wear. The cause of this defective condition resides in the binding of the lower marginal portion of the upper lengthwise of the last under the effect of the toe-end pulling over movement of the pulling over machine whereby the back-seam is disturbed on the heel-end of the last whenever the operator may not have engaged the toe-end of the upper exactly in line with the heel-

end of the last or whenever one side of the upper is of a more stretchy nature than its opposite side.

The pre-stretched lower marginal portion of the shoe upper in accordance with the practice of my method eliminates the above noted defective conditions at the pulling over machine operation.

My method is beneficial also at the side lasting machine operation, which is the third step in the lasting of the shoe, and notably so when the step of stretching the upper heightwise of the last and of fastening to the last the heightwise stretched upper at the ball line of the last until the time of the performance of a pulling over machine operation at or approximately at the ball line of the last, as hereinafter further explained, is availed of in the practice of the method. It is to be noted that this step of stretching the upper heightwise of the last and of fastening the same in stretched condition at the ball line of the last, in conjunction with the prior performed step of stretching its lower marginal portion lengthwise of the last, corresponds with the usual mode of stretching the upper diagonally in a direction toward the toe of the last and simultaneously heightwise of the last at the ball line of the last by the operator of the side lasting machine with hand lasting pincers (whenever the upper has not been pulled-over, as usually the case, at the ball line of the last) preparatory to presenting the shoe to the side lasting machine.

It is to be further noted that my method eliminates also certain defective conditions at the heel-seat lasting machine operation, which is the fourth step in the lasting of the shoe, by stretching the lower marginal portion of the upper and of its lining lengthwise toward of the last whereby the lining is smoothed out from under the counter and the upper is firmly stretched against the counter towards the bottom edge of the heel of the last at the assembling operation which then includes the fastening of the stretched upper to the last, such as at the ball line of the last, whereby it is held in stretched condition and deadened on the heel of the last within the period of time extending from the performance of the assembling operation to the performance of the heel-seat lasting machine operation and whereby wrinkling of the upper and/or of the lining is eliminated at the heel-seat lasting machine operation. Furthermore, the pressing and flattening of the upstanding counter-flange at the "corners of the heel of the last" (commonly termed "dog ears") is contemplated in the practice of my method. The term "corners of the heel of the last" is designated as being located at those points between the rounded end of the heel of the last and the start of the sides of the heel of the last. The upstanding counter-flange at the corners of the heel cause serious disturbance of the counter as a whole on the last under the undue grip and draw of the wipers of the heel-seat lasting machine at those particular points and my method contemplates, as hereinafter further explained, the elimination of such a defective condition at the heel-seat lasting machine operation.

As shown in the accompanying drawings:

Figure 1 shows a side elevation of my shoe upper stretching machine which is adapted to the practice of the herein disclosed method;

Figure 2 shows a front elevation of the said machine;

Figure 3 shows a plan view of the shoe after the performance of the lengthwise stretching operation upon the lower marginal portion of the shoe upper and the subsequent assembling operation upon the heel-end and the sides of the shoe upper by stretching the shoe upper heightwise of the last and then by driving tacks to hold the shoe upper in assembled condition on the last;

Figure 4 shows a view similar to that of Fig. 3, but then the shoe is shown after having been removed from the machine;

Figure 5 shows the tip of the upper clamping means, taken on line 5—5 Fig. 1;

Figure 6 shows a plan view of the oscillating member adapted to oscillate the shoe upper and its lining at the heel-end of the last; and

Figure 7 shows the locking means for holding the shoe upper stretching means from oscillating movement.

As further shown in the drawings:

I have provided the machine-base 1, which rotatably supports the machine-head 2, which has two upstanding arms 3, which support at their upper ends the cross-bar 4, which carries the pivot pin 5, supporting the slide-holding frame 6. The said frame has the forwardly extended arms 7, to which the upper end of a strong spring 8, is connected—the lower end thereof being connected by a pin 9, located on the machine-head 2. The said strong spring urges the said frame 6, upwardly, for purposes to be hereinafter explained, and the said frame has the dovetail track 10, which is adapted to receive the spindle-block 11, which carries the last supporting spindle 12, and the hold-down member 11a, which serves in limiting the upward movement of the last upon the shoe upper stretching means 16, under the influence of the actuating spring 30, moving rearwardly the spindle-block 11, and the last when the treadle 25 is released in the performance of the lengthwise stretching operation upon the lower marginal portion of the shoe upper; and which also serves in pressing and flattening the upstanding flange of the counter, located at the corners of the heel of the last, under the influence of the aforesaid upward movement of the last forcing the heel-seat of the shoe against the said hold-down member 11a, except on lasts of small sizes, as such lasts are not appreciably raised from the last supporting spindle 12, under the effect of the lengthwise stretching operation upon the lower marginal portion of the shoe upper and heel-seats of shoes made on such lasts cannot be, under any circumstances, pressed and flattened against the hold-down member 11a.

In this connection it should be explained that whenever a machine, such as herein shown, is not provided with a hold-down, such as herein shown, the last then, when of a large size or of the high cone type, is moved upwardly and entirely off the last supporting spindle 12, under the influence of the rearward movement of the last upon the shoe upper stretching means 16, by the actuating spring 30, in the stretching of the lower marginal portion of the shoe upper lengthwise of the last. Thus, the upstanding counter-flange, located at the corners of the heel of the last, then may be pressed and flattened against the hold-down member 11a, under the influence of the upward movement of the last from the last supporting spindle 12. The hold-down member 11a, is very important for the practice of the method upon shoes made on large size lasts and

upon shoes made on lasts of the high cone type and notably in limiting the upward movement of such lasts on the last supporting spindle 12, and from entire separation thereof. Of course, a hold-down, such as herein shown, is old in the art and no claim is herein made therefor and, furthermore, it goes without saying, that pressing and flattening of the upstanding counter-flange at the corners of the heel is only incidental to the practice of the method and is not necessary to its practice.

The arms 3, of the machine-head 2, support the bracket 13, which is adjustably mounted for vertical adjustment relatively to the last supporting spindle 12, to accommodate lasts of various styles and the slots 14, and the bolts 15, serve for this purpose. The upper end of the said bracket 13, has a bearing 17, for supporting the shoe upper stretching means 16, and carries a downwardly extended stud 18, which is mounted in the said bearing 17, for oscillation of the heel-end of the shoe upper on the heel-end of the last in smoothing out the lining whenever it is wrinkled on the heel of the shoe. The upper end of the shoe upper stretching means 16, is provided with a hard rubber portion 21, which is adapted to directly engage the top of the upper 22, on the last 23, back of the tip-seam 24, as shown in Figs. 1 and 2 and the sharp front top edge thereof is adapted to hold the curved down forepart portion of the upper from slipping thereon. In this connection it is to be noted, that under the best form of the practice of the method, both sides of the lower marginal portion of the shoe upper, back of its tip-seam, are set into engagement with the members 21a, in advance of the start of the lengthwise stretching operation upon the shoe upper, so that the lower marginal portion of the shoe upper at both its sides may be thereby stretched lengthwise of the last to a predetermined extent (in accordance with the projecting extent of the said members 21a, which may be of any suitable projecting extent depending upon the type or kind of shoe upper to be stretched) in excess of the extent of the stretch upon the top portion of the shoe upper, which takes place towards the end of the stretching operation upon the lower marginal portion of the shoe upper when the slack in the intermediate top portions of the shoe upper has been taken up when both the lower marginal portion of the shoe upper and the intermediate top portions of the shoe upper are respectively stretched lengthwise of the last by the members 21a and by the top front edge of the shoe upper stretching means 16. In this connection it is to be noted that in the stretching lengthwise of the lower marginal portion of the shoe upper, the top portion should then be strained forcibly enough to at least firmly set the upper and the counter against the heel end of the last.

The treadle 25, which carries the connecting rod 26, is pivotally connected to the forward end of the bell-crank lever 27, and the upper end of the bell-crank lever is connected to the link 28, to the sliding-block 11, which carries the downwardly extended hook 29, which holds the forward end of the actuating spring 30—the rear end thereof being secured to the spring-tension adjusting screw 31, which is carried by the downward projection 32, of the track 10.

Locking means are provided for holding the shoe upper stretching means 16, from oscillation and in fixed normal position prior to and

during the time of its operation in the stretching of the lower marginal portion of the shoe upper and to this end the lever 39, is pivotally held at 40, to one of the hand levers 19 and it has an extended locking portion which is adapted to disengage from the recess 42, of the hub 17, whenever the operator depresses the lever 39, to then permit of free oscillation of the shoe upper stretching means 16, as shown in dotted position in Fig. 5. I have further provided the equalizing springs 43, for urging the shoe upper stretching means 16, into straight normal position whereby the locking portion of the lever 39, may automatically engage into the recess 42, of the hub 17 and hold the shoe upper stretching means from oscillation. In this connection it is to be noted that the oscillating movement of the shoe upper stretching means 16, is of very little importance in the practice of the method and is far from being absolutely necessary as there is seldom need for the smoothing out of the lining once the lower marginal portion of the shoe upper and of its lining have been stretched lengthwise from the heel-end to the toe of the last as herein proposed.

I now will explain the practice of the method by the operation of the herein shown machine:

The operator first depresses the treadle 25, whereby the spindle-block 11, is moved forwardly on the track 10 and against the tension of the actuating spring 30 and, while holding the treadle down, he holds the shoe crosswise of the machine and he places the last 23, having an insole 23a assembled thereon and a shoe upper mounted thereon, upon the last supporting spindle 12 and he then places the heel-end of the shoe under the hold-down member 11a, by rotating the shoe on the said spindle until the forepart of the shoe reaches the shoe upper stretching means 16, when he then depresses the forearm engaging member 33, whereby the frame 6, is rocked on the pivot pin 5, against the tension of the strong spring 8 and thus the last supporting spindle 12, is moved, with the shoe thereon, downward to permit of free setting of the forepart of the shoe upon the shoe upper stretching means 16 and then he sets the tip-seam 24, of the upper 22, ahead of the projections 21a, forming part of the shoe upper stretching means 16, and which are adapted to directly engage and hold the lower marginal portion of the shoe upper from slipping rearwardly on the last and he then operates the clamping member 34 (which is herein shown in the form of a rubber roll movable towards and from the top front face of the shoe upper stretching means 16, as shown in its dotted position to its full clamping position in Fig. 1) to thereby hold the tip of the shoe upper against the front face of the shoe upper stretching means 16. Then he releases the treadle 25 and under the action of the actuating spring 30, the spindle supporting block 11, is moved rearwardly and the shoe upper is thereby stretched lengthwise of the last from its heel-end to its toe portion, as hereinbefore explained, and while the shoe upper is being held in stretched condition on the last, he engages and stretches heightwise of the last with hand lasting pincers the upper and its lining at the heel-end of the last and over the insole on the last and he then drives the tack a, through the upper, its lining, the counter-flange and the insole and the tack is clenched against the heel-plate of the last. At this point it is to be noted that the

above explained assembling operation at the heel-end of the last may well be performed prior to the passing of the shoe to the machine herein shown although this assembling operation is better performed, as herein proposed, after the shoe upper has been stretched lengthwise against the heel-end of the last. Then he engages and stretches the upper and its lining (if present) heightwise of the last at or in close proximity to the ball line of the last, first at one side of the last and he then drives tacks *b*, to hold the stretched upper in lengthwise and heightwise stretched and assembled condition on the last at that side of the last and he next proceeds to likewise perform the stretching and assembling operation upon the upper at the opposite side of the last. The tacks *b*, are eventually removed (preferably immediately preceding the performance of the pulling over machine operation upon the upper) to permit of engagement and stretching of the upper and of its lining (if present) at the ball line of the last heightwise of the last by the grippers of the pulling over machine which are adapted to simultaneously engage and stretch the upper at both sides of the last at the ball line of the last. Then he engages and stretches the upper and its lining, and, preferably the counter-flange also, heightwise of the last and diagonally toe-ward of the last and over the insole on the last and he completes the assembling operation in accordance with the best known form of the practice of my method by driving the tacks *c*, to hold the said shoe parts in assembled condition on the last.

It is to be noted that the assembling operation at the ball line of the last, as herein shown, is not absolutely necessary to my invention, as when the shoe upper is of a very stretchy nature this assembling operation may be dispensed with as the reaction upon the shoe upper then is not appreciably disadvantageous and the same is true as to the assembling operation at the sides of the heel of the last whenever the counter exactly or nearly exactly fits the last as then this assembling operation well may be part of the side lasting machine operation.

I have herein shown a shoe of the well known Goodyear welt type for convenience only, it being understood, of course, that the method may be advantageously practiced upon any other type of boots and shoes adapted to be pulled over and/or side lasted by machine.

Each claim is to be interpreted as specifically stated and is to be limited by the requirements of the prior art only.

Having thus explained the nature of my method and shown a machine adapted to the best form of its practice now to be known, what I claim as new and desire to secure by Letters Patent of the United States is:

1. That method of stretching and assembling uppers on lasts which comprises the provision of an upper mounted on a last having an insole assembled thereon and the engaging and stretching of the top portion of the upper lengthwise of the last and the engaging and stretching of its lower marginal portion lengthwise of the last to a predetermined extent in excess of the extent of the lengthwise stretch upon its top portion, preparatory to the performance of the pulling over machine operation upon the upper.

2. That method of stretching and assembling uppers on lasts which comprises the provision of an upper mounted on a last having an insole as-

sembled thereon and the engaging and stretching of the top portion of the upper lengthwise of the last; the engaging and stretching of its lower marginal portion to a predetermined extent lengthwise of the last in excess of the extent of the lengthwise stretch upon its top portion and the fastening of the stretched upper to the insole on the last to hold the stretched upper under lengthwise stretch and in assembled condition on the last, preparatory to the performance of the pulling over machine operation upon the upper.

3. That method of stretching and assembling uppers on lasts which comprises the provision of an upper mounted on a last having an insole assembled thereon and the engaging and stretching of the top portion of the upper lengthwise of the last; the engaging and stretching of its lower marginal portion to a predetermined extent lengthwise of the last in excess of the extent of the lengthwise stretch upon its top portion and the fastening of the stretched upper to the insole on the last at the sides of the heel of the last and at or approximately at the ball line of the last to hold the stretched upper under lengthwise stretch and in assembled condition on the last, preparatory to the performance of the pulling over machine operation upon the upper.

4. That method of stretching and assembling uppers on lasts which comprises the provision of an upper mounted on a last having an insole assembled thereon and the engaging and stretching of the top portion of the upper lengthwise of the last; the engaging and stretching of its lower marginal portion to a predetermined extent lengthwise of the last in excess of the extent of the lengthwise stretch upon its top portion and the fastening of the stretched upper to the insole on the last at or approximately at the ball line of the last to hold the stretched upper under lengthwise stretch and in assembled condition on the last, preparatory to the performance of the pulling over machine operation upon the upper.

5. That method of stretching and assembling uppers on lasts which comprises the provision of an upper mounted on a last having an insole assembled thereon and the engaging and stretching of the top portion of the upper lengthwise of the last; the engaging and stretching of its lower marginal portion to a predetermined extent lengthwise of the last in excess of the extent of the lengthwise stretch upon its top portion and the fastening of the stretched upper to the insole on the last at the sides of the heel of the last to hold the stretched upper under lengthwise stretch and in assembled condition on the last, preparatory to the performance of the pulling over machine operation upon the upper.

6. That method of stretching and assembling uppers on lasts which comprises the provision of an upper mounted on a last having an insole assembled thereon and the engaging and stretching of the top portion of the upper lengthwise of the last; the engaging and stretching of its lower marginal portion lengthwise of the last to some extent in excess of the extent of the lengthwise stretch upon its top portion and the fastening of the stretched upper to the insole on the last at or approximately at the ball line of the last to hold the stretched upper under lengthwise stretch and in assembled condition on the last, preparatory to the performance of the pulling over machine operation upon the upper.

7. That method of stretching and assembling

uppers on lasts which comprises the provision of an upper mounted on a last having an insole assembled thereon and the engaging and stretching of the top portion of the upper lengthwise of the last; the engaging and stretching of its lower marginal portion lengthwise of the last to some extent in excess of the extent of the lengthwise stretch upon its top portion and the fastening of the stretched upper to the insole on the last to hold the stretched upper under lengthwise stretch and in assembled condition on the last, preparatory to the performance of the pulling over machine operation upon the upper.

8. That method of stretching and assembling uppers on lasts which comprises the provision of an upper having a heel portion and mounted on a last having a heel portion and an insole assembled thereon and the engaging and stretching of the top portion of the upper lengthwise of the last from the heel-end thereof and the engaging and stretching of its lower marginal portion simultaneously at both its sides lengthwise of the last from the heel-end thereof to some extent in excess of the extent of the stretch upon its top portion and with or substantially with the same extent of lengthwise stretch at both its sides to thereby avoid undue sidewise displacement of its heel portion relatively to the heel-end portion of the last under the effect of the simultaneous lengthwise stretch taking place upon its lower marginal portion at both its sides, preparatory to the performance of the pulling over machine operation upon the upper.

9. That method of stretching and assembling uppers on lasts which comprises the provision of an upper having a heel portion and mounted on a last having a heel portion and an insole assembled thereon and the engaging of the back of toe top portion of the upper and the stretching of the top of the upper including its engaged back of toe top portion lengthwise of the last from the heel-end thereof and the stretching of its lower marginal portion simultaneously at both its sides lengthwise of the last from the heel-end thereof to some extent in excess of the extent of the stretch upon its top portion and with or substantially with the same extent of lengthwise stretch at both its sides to thereby avoid undue sidewise displacement of its heel portion relatively to the heel-end portion of the last under the effect of the simultaneous lengthwise stretch taking place upon its lower marginal portion at both its sides, preparatory to the performance of the pulling over machine operation upon the upper.

10. That method of stretching and assembling uppers on lasts which comprises the provision of an upper having a heel portion and mounted on a last having a heel portion and an insole assembled thereon and the engaging of the back of toe top portion of the upper and the stretching of the top of the upper including its engaged back of toe portion lengthwise of the last from the heel-end thereof; the stretching of its lower marginal portion simultaneously at both its sides lengthwise of the last from the heel-end thereof to some extent in excess of the extent of the stretch upon its top portion and the fastening of the upper in stretched condition on the last at the sides of the heel and at or approximately

at the ball line of the last, preparatory to the performance of the pulling over machine operation upon the upper.

11. That method of stretching and assembling uppers on lasts which comprises the provision of an upper having a heel portion and mounted on a last having a heel portion and an insole assembled thereon and the engaging of the back of toe top portion of the upper and the stretching of the top of the upper including its engaged back of toe portion lengthwise of the last from the heel-end thereof; the stretching of its lower marginal portion simultaneously at both its sides lengthwise of the last from the heel-end thereof to some extent in excess of the extent of the stretch upon its top portion and the fastening of the upper in stretched condition on the last at or approximately at the ball line of the last, preparatory to the performance of the pulling over machine operation upon the upper.

12. That method of stretching and assembling uppers on lasts which comprises the provision of an upper having a heel portion and mounted on a last having a heel portion and an insole assembled thereon and the engaging of the back of toe top portion of the upper and the stretching of the top of the upper including its engaged back of toe portion lengthwise of the last from the heel-end thereof; the stretching of its lower marginal portion simultaneously at both its sides lengthwise of the last from the heel-end thereof to some extent in excess of the extent of the stretch upon its top portion and the fastening of the upper in stretched condition on the last at the sides of the heel of the last, preparatory to the performance of the pulling over machine operation upon the upper.

13. That method of stretching and assembling uppers on lasts which comprises the provision of an upper mounted on a last having an insole assembled thereon and the engaging and stretching of the top portion of the upper lengthwise of the last; the engaging and stretching of its lower marginal portion lengthwise of the last to some extent in excess of the extent of the lengthwise stretch upon its top portion and the fastening of the stretched upper to the insole on the last at the sides of the heel of the last and at or approximately at the ball line of the last to hold the stretched upper under lengthwise stretch and in assembled condition on that last, preparatory to the performance of the pulling over machine operation upon the upper.

14. That method of stretching and assembling uppers on lasts which comprises the provision of an upper mounted on a last having an insole assembled thereon and the engaging and stretching of the top portion of the upper lengthwise of the last; the engaging and stretching of its lower marginal portion to some extent lengthwise of the last in excess of the extent of the lengthwise stretch upon its top portion and the fastening of the stretched upper to the insole on the last at the sides of the heel of the last to hold the stretched upper under lengthwise stretch and in assembled condition on the last, preparatory to the performance of the pulling over machine operation upon the upper.
